US00D753106S

(12) **United States Design Patent**
Chao

(10) **Patent No.:** **US D753,106 S**
(45) **Date of Patent:** **** Apr. 5, 2016**

(54) **ELECTRONIC DEVICE**

(71) Applicant: **Quasi Stellar Alpha Inc.**, San Francisco, CA (US)

(72) Inventor: **Steve Yi Long Chao**, Milpitas, CA (US)

(73) Assignee: **QUASI STELLAR ALPHA INC.**, San Francisco, CA (US)

(**) Term: **14 Years**

(21) Appl. No.: **29/526,079**

(22) Filed: **May 6, 2015**

(56)
